UNITED STATES PATENT OFFICE.

MILTON J. WILLIAMS, OF CHICAGO, ILLINOIS.

PULVERIZER

939,775.

Specification of Letters Patent.

Patented Nov. 9, 1909.

Application filed February 16, 1909. Serial No. 478,217.

To all whom it may concern:

Be it known that I, MILTON J. WILLIAMS, a citizen of the United States, residing at Chicago, Illinois, have invented a certain 5 new and useful Improvement in Pulverizers, of which the following is a full, clear, and exact description, such as will enable others skilled in the art to which it appertains to make and use the same, reference being had 10 to the accompanying drawings, forming part of this specification, in which—

Figure 1 is a vertical sectional view through a pulverizer constructed according to my improvement. Fig. 2 is a horizontal 15 fragmentary sectional view through the same.

This invention relates to a new and useful improvement in pulverizers of that type commercially known as the "Williams mills," characterized by the pivoted revolving hammers which act upon the material as it enters the machine at the hopper or feed end thereof, crushing said material as it rests upon the bottom of the hopper, or 20 breaker plate, as it is sometimes called, the material being further disintegrated or crushed by the hammers acting thereon as the material is carried over the cage or grinding surface. The crushed material falls 25 through the openings in the cage or grinding surface into a suitable receptacle located beneath the machine. The hammers or beaters which revolve about the shaft, while made of a material whose resistance to wear 30 is its essential quality, will, in time, wear away at their striking ends, and the farther these striking ends are removed from the breaker plate and grinding surface, the less becomes the capacity of the machine.

It is the purpose of my present invention 35 to provide means whereby these revolving hammers or beaters may be adjusted outwardly to take up this wear (or inwardly, if occasion requires, as when a new cage is 40 introduced to replace a worn one), said means consisting of pivotally mounted hammer supports which carry hammers at their outer ends, and whose inner ends coöperate with rods adjustably mounted in disks so 45 that when a rod is adjusted, all of the hammers in that longitudinal row are adjusted.

In the drawings, 1 indicates the casing; 2 the breaker plate, 3 the grinding surface or cage, and 4 the cover of the machine, which 50 may or may not be hung, as desired.

5 is a shaft mounted in the casing, said

shaft having disks 6 fixed thereon, said disks supporting through-bolts 7, on which are pivotally mounted hammer supports 8 in the form of levers whose inner ends are 60 preferably inclined and whose outer ends pivotally support the hammers 9. A single pivot bolt is provided for each row of hammers.

10 are openings in disks 6, said openings 65 being arranged in groups or series, each hole or opening of a series being at a different distance from shaft 5. Rods 11 are fitted in these openings, said rods coöperating with the inner ends of the hammer supports 8.

In operation, when the hammers are new 70 the rods 11 are positioned in the innermost openings 10. As the hammers wear, rods 11 are taken out and inserted through openings 75 farther away from shaft 5, these changes in the position of rods 11 being from time to time, as the hammers wear.

I am aware that it is old to mount hammers on pivot bolts which may be withdrawn and inserted in other openings of a series farther removed from the shaft of the machine, to take up wear of the hammers. Such a construction, however, requires some 80 little time to effect an adjustment of the 85 hammers, because the row of hammers, when the pivot bolts are removed, have to be re-adjusted in alinement with the selected opening, according to the adjustment required.

90 By my present construction, mounting the hammers on levers enables me to effect the adjustment of the striking ends of the hammers without dismantling the row of hammers, the hammers remaining in their 95 mounts during the time that the adjustment is being effected.

I am aware that minor changes in the construction, arrangement and combination of the several parts of my device can be 100 made and substituted for those herein shown and described, without in the least departing from the nature and principle of my invention.

In using the expression "disks" in the 105 foregoing specification and in the following claims, I wish to be understood as not confining myself to circular disks, as the parts which perform the functions of the supporting disks described and claimed could be 110 in the shape of spider-arms, or other forms, metal being cut away at various places,

where it was not needed, to lighten the machine.

Having thus described my invention, what I claim is:

- 5 1. In a pulverizer, the combination with a casing, of a shaft, disks mounted on said shaft, hammer supports pivotally mounted between said disks, revolving hammers pivotally carried by said supports, rods mounted in said disks against which the inner ends of the hammer supports engage, and which rods are adjustable in the disks whereby the wear of the hammers may be taken up.
- 10 2. In a pulverizer, a casing, a shaft journaled therein, disks mounted on the shaft, a series of rods removably seated in the disks, a series of hammer supports pivotally mounted on each of the rods, hammers carried by said hammer supports and adjustable means seated in the disks and co-operating with the inner portions of the hammer supports for effecting the adjustment of the hammers.
- 15 3. In a pulverizer, a casing, a shaft journaled therein, disks mounted on the shaft, a series of sets of hammer supports pivotally

carried between the disks, angular projections on the inner ends of the hammer supports, means adjustably seated in the disks and engaging the angular projections on the ends of said hammer supports, and hammers pivotally carried by the outer end of the hammer supports.

4. In a pulverizer, a casing, a shaft journaled therein, disks mounted on said shaft, said disks having a series of sets of openings, each opening of a set being at a different distance from the shaft than the other openings, rods arranged to be inserted in any of said openings, hammer supports pivotally arranged between the disks, angular projections on the inner ends of said hammer supports, which projections co-operate with said rods and hammers carried by the outer ends of the hammer supports.

In testimony whereof I hereunto affix my signature in the presence of two witnesses, this 8th day of February, 1909.

MILTON J. WILLIAMS.
